METHOD OF MAKING A TISSUE PAPER PRODUCT

Charles A. Fourness, Appleton, and James T. Whelan, Menasha, Wis., assignors to International Cellucotton Products Company, Chicago, Ill., a corporation of Delaware

Application June 1, 1935, Serial No. 24,530

3 Claims. (Cl. 154—33)

This invention relates to tissue paper products, and particularly to tissue paper products made from tissue paper which is inherently soft, for example, very thin crepe tissues such as are called "facial" or "cleansing" tissues.

The main objects of the invention are to provide an embossed, soft tissue paper product which has an especially attractive appearance but which despite the embossing, retains and possibly enhances the normal or inherent softness of ordinary soft, creped, unembossed tissue paper articles, such as cleansing or facial tissues made according to the usual practice heretofore in general use. It is also an object of this invention to provide practicable means for producing a product such as described.

Other objects and advantages of the invention will appear by reference to the following specification and accompanying drawing in which there is illustrated a portion of an embossed tissue paper article which, in accordance with this invention, has the inherent softness of unembossed, very thin, and inherently soft crepe tissue paper and a preferred method of making the same.

In the drawing—

Figs. 1 and 2 are diagrammatic illustrations of successive steps in the method of treating the paper webs from which the cleansing tissue sheet or like product is formed;

Fig. 3 is an enlarged section on the line 3—3 of Fig. 2;

Fig. 4 is a fragmentary plan of an embossing roll (on an enlarged scale) illustrating one form of embossing which may be used to advantage in accordance with the invention;

Figs. 5 and 6 are sections on the lines 5—5 and 6—6 respectively of Fig. 4;

Fig. 7 is a fragmentary plan of a sheet of creped tissue paper showing a portion thereof treated in accordance with the present invention, and

Fig. 8 is a diagrammatic illustration of certain conditions which exist in the production of an article embodying this invention.

Referring now to the drawing, there is diagrammatically illustrated in Fig. 1 the dryer or delivery roll 10 of any form of paper machine on which tissue paper is produced. The web of tissue paper designated 11 is delivered to the dryer roll 10 by means of a felt belt 12, the point of delivery being preferably near the point of removal of the web from the dryer so that the largest possible area of the dryer roll is utilized.

The web of paper 11 is preferably removed from

the dryer roll by means of a doctor blade 13 whereby the paper web is creped. The direction of the creping, that is, the striations of the crepe paper extend transversely of the length of the web, and the creped web designated 14 is wound into a roll 15, in accordance with more or less conventional practice.

Cleansing tissues are preferably made of two plies of the creped tissue stock. Therefore, to provide a two-ply web of creped tissue paper, two rolls 15 of the creped tissue are suitably mounted to permit withdrawal therefrom of their respective webs and super-position of the latter to form a multi-ply web. The multi-ply (in this instance, two-ply) web is fed between a set or sets of calender rolls 16 which serve to crush some of the striations of the creping. The calender rolls may also be driven at such speed relative to the rate at which the supply rolls are driven, or one pair of calender rolls may be driven at increased speed relative to the other, as to effect stretching out of some of the creping in the webs.

The multi-ply web is then fed between a hard embossing roll 17 and a platen roll 18 having a soft and resilient covering 19.

The pattern of embossing on the hard roll, which may be of steel, is preferably an all-over pattern and by way of example it may consist of a multiplicity of small, more or less rounded oblong projections which are spaced from each other a distance which is less than the width of the projections. Such a pattern is illustrated, greatly enlarged, in Figs. 4 to 7 inclusive. Other patterns may be employed but it is preferable that the pattern be a small one, which will effect embossing not materially coarser than the creping in the webs, and preferably such that all of the lines of creping are interrupted.

The steel roll may conveniently, but not necessarily, be approximately nine and one-half inches in diameter. With such a steel roll, the platen roll may conveniently be about fourteen inches in diameter. The resilient jacket forming a part of the platen roll is preferably about three quarters of an inch in thickness and of a density which will give a plastometer reading of 45 to 50 with a one-eighth inch ball. The outer surface of the rubber jacket is substantially smooth and plain.

Only the steel embossing roll need be driven and it is preferably adjusted to the platen roll so as to produce a pressure which is sufficient to produce a satisfactory embossing effect on the crepe tissue paper fed between the rolls. The pressure which has been successfully employed is

sufficient to cause a compression of about one thirty-second of an inch in the rubber roll jacket and a contact zone between the roller of about seven-eighths of an inch in width. This condition is diagrammatically represented on an enlarged scale in Fig. 8.

From an examination of Fig. 8, it will be seen that sheets fed between the rolls are subjected to a gradually increasing pressure until the maximum embossing pressure is applied in the middle of the width of the contact zone. The pressure applied to sheets to be embossed starting at the initial point A of contact between the rolls rises fairly rapidly as the sheet progresses between the rolls until about one-fifth or some such portion of the width of the zone of contact is traversed. Then the applied pressure rises somewhat more slowly until the middle point of maximum pressure is reached. From there on the pressure first slowly, and then more rapidly decreases until the embossed sheet emerges from the contact zone. If the normal pressure applied is, say 250 pounds per lineal inch of the contact zone, the maximum pressure, at the middle of the contact zone will be considerably greater, as indicated in the diagram Fig. 8.

It will be observed that the creped tissue sheets are gripped over a band corresponding to the zone of contact between the rolls. By this means, the sheets are effectively supported and held against slipping or creeping between the rolls and the initial area of the webs or sheets is not reduced as a result of the embossing. In other words, the embossing requires actual stretching of the sheet material, rather than a gathering effect such as results from conventional embossing methods where the embossing is effected along a line of contact between rolls, as distinguished from an area of contact as in the disclosure in this application.

By reference to Fig. 2, it will be noted that the multi-ply creped tissue web has the striations of its creping extending transversely of the length of the web, so that when the web is embossed between the steel roll 17 and the rubber covered roll 19, the longitudinal direction of the elongated embossing pattern will extend transversely of the creping of the paper. As indicated in the drawing, especially Fig. 7, the described embossing forms a pattern which is not materially coarser than the creping of the paper, and serves to break up the continuity of the creping. The embossed sheets tend to have or approximate the appearance of woven textile material such as linen, the creping in the sheets serving to produce the characteristic irregularity of such material. The embossed web may then be severed into independent cleansing tissue sheets or otherwise treated to prepare the web for marketing.

One design of embossing such as typified by that herein illustrated is such that there are approximately 30 circumferentially extending lines of embossing to the inch and such that there are about 24 transversely extending lines to the inch. A pattern of such proportions produces excellent results.

The speed of rotation of the rolls appears to be of no great importance and they may be driven at any speed desired or necessary for the required production. The rolls are not geared together but operate independently, only the steel emboss-

ing roll being positively driven. The other roll will of course follow the driven roll incident to the operating contact between their surfaces.

The embossing of paper napkins and other paper articles with various designs is of course an old practice but so far as known, no one has heretofore attempted to emboss crepe tissue paper with an all-over design for any purpose such as herein contemplated. Paper embossing as practiced in the prior practical art is usually accomplished between a steel embossing roll and a hard paper or other composition roll which has been run in with the steel roll so as to have a permanent impression on its surface which is complementary to the raised design of the embossing of the steel roll. This form of apparatus cannot successfully be used for the purpose of embossing crepe tissue paper, for the reason that when crepe tissue paper is embossed in that manner the resulting product is hardened or stiffened so as to become wholly unfit for any of the uses to which creped tissue paper is put because of its normal softness.

The described arrangement is illustrative of one practical method and suitable apparatus for producing an improved, inherently soft tissue paper product. Changes may be made in the described arrangement without departing from the spirit of the invention, the scope of which should be determined by reference to the following claims, the same being construed as broadly as possible consistent with the state of the art.

We claim:

1. The method of making a tissue paper sheet suitable for facial and like uses, which consists in conducting a creped tissue paper sheet through a pressure zone of substantial length whereby the concentration of pressure at any point of the pressure zone is insufficient to produce any hardening of the material while simultaneously, by means of said pressure, forming in the sheet an all-over pattern not materially coarser than the creping in the sheet.

2. The method of making a crepe tissue paper sheet suitable for facial and like uses, which consists in conducting a creped tissue paper sheet through the nip of a pair of embossing rolls, the pattern roll of which is made of hard material bearing an all-over design not materially coarser than the original creping in the paper sheet, and the platen roll of which has a smooth, soft, resilient rubber surface, said rolls being so juxtaposed and the softness of said platen rubber being such that the rubber of the platen roll is compressed to form said nip of substantial length whereby the concentration of pressure at any point of said nip is insufficient to harden the crepe tissue paper while the pressure is sufficient to impress the pattern of said pattern roll in said paper.

3. A paper article of such softness as to be suitable for facial and like uses, comprising a creped tissue paper sheet having an all-over pattern embossed therein, the pattern being not materially coarser than the creping and comprising a multiplicity of elements separated by interposed areas of the sheet which remain substantially in their initially soft condition.
